The ornamental design for an electronic equipment power amplifier module, as shown and described.

DESCRIPTION

FIG. 1 is a perspective view of the front, top, and right side of an electronic equipment power amplifier module showing a first embodiment of our new design;

FIG. 2 is a left elevational of the first embodiment;

FIG. 3 is a rear elevational view of the first embodiment;

FIG. 4 is a bottom plan view of the first embodiment;

FIG. 5 is a top, right and front perspective view of an electronic equipment power amplifier module showing a second embodiment of our new design;

FIG. 6 is a top plan view of the first embodiment;

FIG. 7 is a right side elevational view of the first embodiment;

FIG. 8 is a left side elevational view of the second embodiment;

FIG. 9 is a rear elevational view of the second embodiment; and,

FIG. 10 is a bottom plan view of the second embodiment.
